The ornamental design for a portable fiber optic camera, as shown and described.

DESCRIPTION

FIG. 1 is a front and right side perspective view of a portable fiber optic camera showing our new design.

FIG. 2 is a rear and right side perspective view thereof.

FIG. 3 is a left side elevation view thereof.

FIG. 4 is a right side elevation view thereof.

FIG. 5 is a rear elevation view thereof.

FIG. 6 is a front elevation view thereof.

FIG. 7 is a top plan view thereof; and,

FIG. 8 is a bottom plan view thereof.

The broken lines depict portions of the portable fiber optic camera in which the design is embodied that form no part of the claimed design. Additionally, the dash-dot lines on the left, right, and rear sides of the portable fiber optic camera denote the boundary of the claim and form no part of the claimed design.
